AUTOMATIC COAL STOKING DEVICE

Leonard H. Segar, Renton, Wash.

Application August 9, 1934, Serial No. 739,154

4 Claims. (Cl. 110—109)

This invention relates in general to furnace devices, and more particularly has reference to an automatic coal stoker, particularly adaptable to household installations.

5 While automatic coal stoking devices have been provided for household use previous to this time, they have generally been complex in assembly and expensive of construction. Also the mechanisms have usually been liable to clogging with 10 coal and have burned fuel ineffectively. There has in addition often been a back tracking of gases rendering the machines objectionable.

The devices used in the past have for the most part required alterations or actual changes in 15 conventional furnace constructions. This has, of course, rendered the use of automatic stokers almost prohibitive in small installations and exceedingly expensive where otherwise suitable furnace equipment has been available.

20 An object of this invention is to provide an automatic coal stoking device embodying a minimum of parts and simple in operation.

Another object of this invention is to provide an automatic coal stoking device adaptable to 25 any conventional furnace installation.

Still another object of this invention is to provide an automatic coal stoking device having a force draft arrangement providing for efficient burning of the fuel and preventing back tracking 30 of gases.

Still another object of this invention is to provide an automatic coal stoking device which will feed evenly and without clogging.

A still further object of this invention is to 35 provide an automatic coal stoking device which will feed fuel at a uniform depth for even burning.

40 A further object of this invention is to provide an automatic stoking device embodying a conveying trough, also forming a grate.

A still further object of this invention is to provide an automatic stoking device having a 45 step grate for breaking up the fuel and allowing for the introduction of air to promote combustion.

A still further object of this invention is to provide an automatic coal stoking device including an adjustable feeding mechanism.

With these and other objects in view, which 50 may be incident to my improvements, the invention consists in the parts and combinations to be hereinafter set forth and claimed, with the understanding that the several necessary elements comprising my invention may be varied in construction, proportions and arrangement, without 55

departing from the spirit and scope of the appended claims.

In order to make my invention more clearly understood, I have shown in the accompanying drawing means for carrying the same into practical effect without limiting the improvements in their useful applications to the particular constructions, which, for the purpose of explanation, have been made the subject of illustration.

In the drawing forming part of the specification:

Fig. 1 is a longitudinal section view of my novel automatic coal stoking device, shown installed in a conventional furnace.

Fig. 2 is a sectional view taken on line 2—2 of Fig. 1.

Fig. 3 is a side view partly in section, showing my adjustable feeding mechanism.

Fig. 4 is a sectional view taken on line 4—4 of Fig. 2.

Fig. 5 is a sectional view taken on line 5—5 of Fig. 2.

Referring more particularly by numerals to the drawing in which the same and similar elements are designated by like symbols of reference throughout, and more especially to Fig. 1, there is shown my novel automatic coal stoking device in conjunction with a conventional household furnace installation.

It will be seen that my automatic stoker comprises a hopper, 1, open at the top for receiving coal indicated by the numeral 2. The hopper is mounted at the outer end of a steel stoker body casing, 3, comprising a bottom and sidewalls, 4 and 5, as shown in Fig. 4, and opens therein, as shown by the numeral 6 in Fig. 2.

The coal, 2, is adapted to feed through the hopper into a cast-iron trough, 7, mounted in the casing, 3, as shown in Fig. 4. The trough, 7, is formed with side walls, 8 and 9, and angle pieces, 10 and 11, are secured thereto along the rim by bolts, 12.

The angle pieces are adapted to slide on inwardly extending flanges, 13 and 14, formed on the rims of the sidewalls, 4 and 5, on the casing, 3, as is also shown in Fig. 4. The casing, 3, is provided with a top closure, 15, having downwardly extending sides, 16 and 17, secured to the sides, 4 and 5, of the casing, 3, by bolts, 18.

The trough, 7, for receiving the coal, 2, is adapted to reciprocate longitudinally in the casing, 3, the angle pieces, 10 and 11, secured thereon, sliding on the bearing slide rails formed by the flanges, 13 and 14, on the rims of the sides, 4 and 5, of the stoker body casing, 3.

An open top cast-iron casing, 19, is attached to the front end of the stoker body casing, 3, by bolts, 20. A series of spaced step grate bars, 21, angularly arranged with respect to the horizontal 5 are fixed to the end of the conveyor trough, 7, by mounting between downwardly extending sides, 22, formed thereon. The first grate bar is spaced twice the distance from the bottom of the trough 7 that the succeeding grate bars are 10 spaced from each other.

The rear end of the stoker body casing, 3, extends in a housing, 23, comprising top, bottom and side portions, for enclosing a driving mechanism. A stationary steel back stay, 24, for fitting in the rear of the conveyor trough, 7, is fixed 15 to the housing, 23, and braced against a gear box, 25, mounted in the housing, by a bracket, 26. The back stay is steel welded and the top forms a saddle for mounting the hopper. The bottom of 20 the stay, 24, is formed with a scraper edge composed of stainless steel for working on a wearing plate, 27, of the same material bolted in the conveyor trough. The stay and wearing plate have a valve-like action which provides for relative movement indefinitely without coal leaking 25 in past.

The back stay, 24, being stationary, coal fed into the reciprocating conveyor trough from the hopper will contact therewith and move forward 30 relative to the trough on each outward stroke of the trough. On the inward stroke of the trough additional coal from the hopper will be fed therein.

The driving mechanism enclosed in the housing, 23, comprises a driving shaft, 28, extending through a journal, 29, and fitted in an end journal, 30, as shown in Fig. 2. A worm gear, 31, is keyed on the shaft for engaging a gear, 32. The gears, 31 and 32, are enclosed in the gear box, 25, in the housing, 23. The gear, 32, is adapted to drive a crank arm formed by an eccentric, 33, having a pin, 34, seated thereon.

The shaft, 28, has a pulley, 35, keyed on the end thereof for driving by a motor, 36, mounted 45 on the rear end of the stoking device, through a flexible driving mechanism, 37. The pulley and flexible driving mechanism are enclosed in a further supplemental housing, 38, attached to one side of the housing, 23.

The motor, 36, is also adapted to drive a conventional blower enclosed in a housing, 37. The blower communicates with a conduit, 38', as shown in Fig. 1, opening into the casing, 3, under the trough, 7.

The rear end of the automatic stoker assembly 55 is supported on a mounting leg, 39, and the front end in the opening provided in a furnace for receiving the casing, 3.

The conveyor trough, 7, is adapted to be connected to the crank arm through a lost-motion connecting rod. This comprises a threaded rod, 40, having an eye, 41, formed on one end for engaging the pin, 34, and accommodating ball-bearings, 42, and inner and outer races, 43 and 44; and a reduced extension, 45, formed on the other end. The reduced extension, 45, is fitted through a knuckle head, 46, fixed on a pin, 47, which is pivoted in a draw bar, 48, fixed on the rear end of the conveyor trough. The reduced extension, 45, is formed with a further reduced threaded extension, 49, adapted to receive a washer, 50, and nut, 51, for securing the connecting rod in the knuckle, 46.

It will be apparent that the reduced extension, 45, will reciprocate in the knuckle, 46, with a con-

sequent loss of motion throughout its length. A threaded sleeve, 52, having a collar, 53, formed on one end, is screwed on the connection rod, 40, together with a collared lock nut, 54.

The sleeve, 52, is adapted to provide for shortening the play of the reduced extension, 45, in the knuckle, 46, and is provided with the bumper, 55, on the end. The sleeve, 52, thus intended for taking up lost motion is locked in place by the nut, 54.

The eccentric for reciprocating the conveyor trough is mounted on a vertical shaft, 56, journaled in the gear box, 25, and having the gear, 32, keyed thereon. A spacer, 57, is interposed between the underside of the eccentric, 33, and the top of the gear box, 25.

A felt deflector, 58, is mounted in the stoker body casing, 3, around the conveyor trough, 7, on a support, 59, to act as an air stop and prevent the back tracking of air to the gear box chamber.

The casing, 3, is adapted to be extended within a furnace through the door or other opening as indicated in Fig. 1, and any remaining space around the casing enclosed in any suitable manner.

The operation of my invention will be readily understood from the foregoing description.

The conveyor trough, 7, is adapted to receive coal, 2, adjacent the rear end from the hopper. The conveyor trough is adapted to be reciprocated 30 by the motor, 36, driving the crank arm, 34, through the series of reducing gears in the box, 25, and through the lost-motion connecting rod, 40, in the housing, 23.

The length of the stroke of the conveyor trough is adapted to be adjusted through manipulation of the sleeve, 52, to lengthen or shorten the travel of the reduced extension, 45, in the knuckle, 46. The stroke of the conveyor is shortened by allowing the full length of the reduced extension, 45, to reciprocate in the knuckle, 46, or reversely the stroke lengthened by screwing the sleeve, 52, to take up the play of the reduced extension, 45, in the knuckle.

The housing, 23, may be provided with a cover 45 to allow access to the adjustable drive mechanism.

As the trough is reciprocated, coal from the hopper will fall therein and be moved inward relative to trough by contact with the stationary back stay, 24, on each outward stroke of the trough. The hopper and reciprocating trough arrangement insure against clogging, as any enlarged object will remain in position without damage to the apparatus and coal will feed there-around. As the conveyor and firepot move together the coal is fed on the grates the same depth as in the conveyor trough due to the top, 15, limiting the depth of coal therein. This it will be readily perceived overcomes the disadvantage of 55 a stationary firepot wherein the coal is piled up at the outlet so as to build up an uneven fuel bed.

The step grate tends to break up the coal as it passes thereon for burning. As the grates are angularly arranged the air directed therethrough 65 from the blower is fed in to the coal at a slight angle off the parallel of the coal feed. This charges the fuel with air instead of allowing the escape of the gases before combustion, as otherwise would obtain if the air was directed at right 70 angles to the fuel feed. The air on the first grate as the coal leaves the conveyor is double in volume to that on each succeeding grate. The reason for this is that the pre-heated coal, as it leaves the level of the conveyor, has begun to release vola- 75

tile gases and it is necessary to drive a heavy stream of air into these gases and carry them into combustion. This method of applying the air gives a clean fire with no back tracking of gases 5 through the fuel tunnel and out of the hopper, as has been a serious and dangerous disadvantage in many prior stoking devices.

The casing 19 does not touch or support the conveyor trough or fire pot. It is provided to 10 prevent a loss of air and to direct the air through the grates. A slight clearance between the casing and fire pot allows sufficient air to flow there-between to prevent burning out of the fire pot. A small quantity of air is liberated over the sides 15 of the conveyor from the stoker body casing, 3, which forms an over-draft into the fire and assists in combustion by spreading the flames over a greater area.

The wearing plate, 21, in the conveyor trough 20 prevents the leakage of coal to the rear and the felt, 58, around the conveyor trough prevents the back tracking of fuel-laden air.

In addition to the foregoing, a thermostat may be provided in conjunction with the blower to 25 vary the quantity of air as the heat in the fire pot varies.

The stoker body casing may be extended in the conventional opening in a furnace and any remaining space cemented up with fire brick or the 30 like.

There is accomplished by this invention an automatic coal stoking device particularly adaptable to household installations, embodying a minimum number of parts and simple in assembly, and adaptable to any conventional furnace installation, which provides for efficiently burning fuel at an even depth without back tracking of gases, allowing for the efficient introduction of air to promote combustion and embodying an 40 adjustable feeding mechanism.

While I have shown and described the preferred embodiment of my invention, I wish it to be understood that I do not confine myself to the precise details of constructions herein set forth, 45 by way of illustration, as it is apparent that many changes and variations may be made therein, by those skilled in the art, without departing from the spirit of the invention or exceeding the scope of the appended claims.

50 I claim:

1. In combination with a furnace, an automatic coal stoking device comprising a horizontal casing having one end extending through the furnace wall, a trough mounted for sliding movement in the casing, a stepped grate secured to the in-

ner end of the trough and arranged to receive fuel therefrom, a hopper for delivering coal into the outer end of the trough, means to reciprocate the trough, stationary means adjacent the outer end of the trough for cooperating with the trough to push the coal onto the grate, and means to direct a current of air into the casing under the trough and through the grate.

2. In combination with a furnace, an automatic coal stoking device comprising a horizontal casing having one end extending through the furnace wall, a trough mounted for sliding movement in the casing, a stepped grate secured to the inner end of the trough and arranged to receive fuel therefrom, means for delivering coal into the outer end of the trough, a driving mechanism embodying a motor, a series of reduction gears, a crank arm and a lost motion connecting rod reciprocating the trough in the casing, and a stationary stay adjacent the outer end of the trough for cooperating with the trough to push the coal onto the stepped grate on each outward stroke of the trough.

3. In combination with a furnace, an automatic coal stoking device comprising a horizontal casing having one end extending through the furnace wall, a trough mounted for sliding movement in the casing, a stepped grate attached to the inner end of the trough and arranged to receive fuel therefrom, means for delivering coal into the outer end of the trough, a driving mechanism for reciprocating the trough, stationary means adjacent the outer end of the trough for cooperating with the trough to push the coal onto the grate on each outward stroke of the trough, and means to adjust the length of the stroke of the trough.

4. In combination with a furnace, an automatic coal stoking device comprising a horizontal casing having one end extending through the furnace wall, a trough mounted for sliding movement in the casing, a stepped grate attached to the inner end of the trough and arranged to receive fuel therefrom, means for delivering coal into the outer end of the trough, a driving mechanism for reciprocating the trough, stationary means adjacent the outer end of the trough for cooperating with the trough to push the coal onto the grate on each outward stroke of the trough, and an adjustable lost motion connecting rod for varying the length of the stroke of the trough to control the quantity of coal pushed on the grate.

LEONARD H. SEGAR.
